UNITED STATES PATENT OFFICE.

ARTHUR A. IRWIN, OF PHILADELPHIA, PENNSYLVANIA.

FIELD-BOARD FOR REPORTING FOOT-BALL GAMES.

SPECIFICATION forming part of Letters Patent No. 633,847, dated September 26, 1899.

Application filed September 24, 1895. Serial No. 563,520. (No model.)

To all whom it may concern:

Be it known that I, ARTHUR A. IRWIN, of Philadelphia, in the county of Philadelphia and State of Pennsylvania, have invented certain new and useful Improvements in Field-Boards for Reporting Foot-Ball Games, of which the following is a specification.

This invention has relation to score-boards for reporting the progress of and plays made in foot-ball games at points remote from the field.

It is the object of the invention to provide such improvements in foot-ball score-boards as will indicate the movement of the ball upon the field by yard or other distances or spaces, so that the onlooker may know from the board not only the points and "plays" made, but the exact position of the ball from time to time as the game progresses as well.

In a patent granted to me dated March 6, 1894, I have shown and described a foot-ball score-board by which with movable slides or panels and inscriptions it may be indicated upon the field or elsewhere as to who is the possessor of the ball, the number of downs, yards to gain, &c. While this board is quite complete for indicating the progress of the game when used upon the field while the game is in progress and is essential to give a clear understanding by means of a bulletin of the plays made at points remote from the field, it is lacking in means for indicating the changing positions of the ball upon the field.

To these ends my invention consists of an improvement in foot-ball score-boards embodying in its construction a board or panel indicating the foot-ball field, which board is provided with parallel lines or graduated scale-marks indicating yards or other specific distances or measurements upon the field from the middle or center to the goals, combined with an object representing the ball movable upon the said scale-board across the said parallel lines and between the representations of the goals, so as to indicate the exact position of the ball upon the field with reference to the center and the goals, in combination with other devices and features, all as I will now proceed to describe and claim.

Reference is to be had to the annexed drawings, and to the letters marked thereon, forming a part of this specification, the same let-

ters designating the same parts or features, as the case may be, wherever they occur.

Of the drawings, Figure 1 is a face view of 55 my improvement, showing it as connected with a score-board, in conjunction with which it is adapted to be employed. Fig. 2 is a vertical sectional view taken on the line 2 2 of Fig. 1.

In the drawings, *a* designates a score-board of a construction substantially the same as that patented to me, as aforesaid, which score-board is constructed and arranged so as to show the "points" and plays made during 65 the progress of a game of foot-ball, which score-board is adapted for use upon the field or as a bulletin off the field.

b designates my improvement, which consists of a field-board adapted to be used alone 70 or in connection with the score-board to show the position of the ball upon the field with reference to the center *c* and the goals H Y.

The board *b* is scaled by means of vertically-drawn parallel lines, which lines are 75 numbered at desired points, so as to make them indicate, say, five yards of distances or spaces upon the field, beginning with five yards from the goal-lines and running up 80 from each end to fifty yards at a line within five yards from the center or middle *c*.

d designates a slot formed in the board *b* and extending across the vertical parallel lines inscribed thereon, the said slot reaching from substantially one goal-indicating point 85 to the other.

e designates an object representing the foot-ball, which object is provided with a stud *f*, extending into the slot *d*, so as to support the ball-representing object *e* and permit it to be 90 moved to any point along the length of the board from goal to goal.

The shank *f* may have a knob *g* formed on the rear thereof, so as to permit the object *e* to be moved along the slot from the rear of 95 the board, or it may be moved from the front by merely taking hold of the object *e* itself. I have contemplated suspending the object *e* upon the board or supporting it in other ways in front thereof, so as to permit it to be moved 100 along the latter unprovided with a slot, and by this means I attain the same end as with the construction herein shown in the drawings; but what is portrayed in the latter is

sufficient to give those skilled in the art a full and clear understanding of the nature of the invention.

Having thus explained the nature of the invention and described a way of constructing and using the same, though without attempting to set forth all of the forms in which it may be made or all of the modes of its use, it is declared that what is claimed is—

10. A foot-ball field and score board, comprising in its construction a board having a miniature representation of a foot-ball field, the lines representing the five-yard lines of the field being substantially vertical, the said board having also a substantially horizontal guideway, and a movable object to indicate

the ball movable along said guideway, and the board being also provided with movable indicators for announcing the points and plays, whereby both the position of the ball 20 and the points and plays of a foot-ball game may be visibly reported during the progress of said game.

In testimony whereof I have signed my name to this specification, in the presence of 25 two subscribing witnesses, this 15th day of August, A. D. 1895.

ARTHUR A. IRWIN.
